UNITED STATES PATENT OFFICE.

JAMES W. BARNES, OF YOUNGSTOWN, OHIO.

REGENERATING-FURNACE.

1,186,370.

Specification of Letters Patent. Patented June 6, 1916.

Application filed June 17, 1915. Serial No. 34,697.

To all whom it may concern:

Be it known that I, JAMES W. BARNES, a citizen of the United States, residing at Youngstown, in the county of Mahoning and State of Ohio, have invented a new and useful Regenerating-Furnace, of which the following is a specification.

This invention relates to regenerating furnaces. Furnaces of this type as heretofore used employ opposed gas nozzles and opposed air passages, the products of combustion, after passing through the hearth chamber, being drawn off through both the air passages and the gas nozzle. This has resulted in subjecting the mouth of each gas nozzle to the action of the intensely hot outflowing gases with the result that the nozzles have soon broken down, thus rendering the furnace unfit for further use until partly reconstructed.

One of the objects of the present invention is to provide a regenerating furnace having means whereby communication between each gas nozzle and the gas chamber communicating therewith is cut off at the outflow end of the furnace so that the hot products of combustion will pass from the furnace solely through the air outlets.

A further object is to provide a novel arrangement of ports and valves by means of which the gas nozzle at the supply end of the furnace will be placed in communication with its gas chamber simultaneously with the cutting off of communication between the other gas nozzle and its gas chamber.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a vertical longitudinal section through a furnace embodying the present improvements, the gas nozzles being shown in section. Fig. 2 is a section on line A—B Fig. 1. Fig. 3 is a section on line C—D Fig. 1. Fig. 4 is a section on line E—F Fig. 1. Fig. 5 is a section on line G—H Fig. 1. Fig. 6 is a section on line

I—J Fig. 2. Fig. 7 is a detail view of one of the valves. Fig. 8 is a view showing in diagram the courses of the air, gas and products of combustion through the furnace.

Referring to the figures by characters of reference 1 designates the hearth chamber of the furnace and arranged at opposite ends thereof are centrally disposed gas nozzles 2 the tops of which are inclined downwardly toward the hearth chamber. The outlet end 60 of each nozzle may be provided with a water jacket 3 extending upwardly along the sides and transversely along the top thereof, this water jacket having outlet pipes 4 extending rearwardly therefrom and along the top 65 of the nozzle and having inlet pipes 5 extending into the sides thereof as shown particularly in Fig. 4.

Extending downwardly from the back portion of the bottom of each nozzle 2 is a 70 gas port 6 with which communicates a gas chamber 7 the bottom of which forms a slag pocket as shown at 8. The chamber 7 is separated from a regenerating or checker chamber 9 by a partition 10 having an intermediate portion 11 extending at right angles and provided with a port 12. Another partition 13 separates the chambers 7 and 9 from an air chamber 14 in constant communication with an air regenerating chamber 80 15. A port 16 extends through the partition 13 and is in alignment with the port 12. A deflector 17 extends from partition 13 and between chamber 14 and the regenerating chamber 15. Slidably mounted between the 90 two ports 12 and 16 is a block 18 carrying a valve 19 from one face of which extends a rod 20. This valve is so arranged that, when moved in one direction it will close the port 16 and open the port 12, and, when moved in the opposite direction, it will close the port 12 and open the port 16. A gas inlet flue 21 opens into the gas regenerating chamber 9 from a gas producer, not shown, and an air inlet flue 22 opens into the bottom portion of the regenerating chamber 15. Extending upwardly from the chamber 14 are spaced air passages 23 which open into the furnace at opposite sides of the back portion of nozzle 2, as shown at 24.

It is to be understood that each end of the furnace is constructed as hereinbefore described and the rods 20 extending from the two valves 19 are connected to a piston 25 arranged within a cylinder 26 located under 100 105 110

the hearth chamber. Thus by directing fluid under pressure into one end of the cylinder 26, the port 16 at one end of the furnace will be closed, while the corresponding port at the other end of the furnace will be opened whereas, when the movement of the piston 25 is reversed, the positions of the valves will be reversed.

The damper mechanism for reversing the flow of gases within the furnace has not been illustrated but is of the form usually employed in furnaces of this type. When a flame is directed into the hearth chamber from the left end of the furnace, for example, the valves are positioned as shown in Fig. 2 so that the gas entering the regenerating chamber 9 from the flue 21 will be free to flow through port 12 and into chamber 7 and thence through the passage 6 to the nozzle 2, while air entering the chamber 15 at the left of the furnace will be free to flow through the chamber 14 and passages 23 to the openings 24 at the sides of the nozzle 2. Thus the air and gas will mix at the mouth of the nozzle to form a combustible mixture. While the valve at the left of the furnace is in position to allow the flow of gas through the nozzle 2 and of air through the passage 23, the valve 19 at the right of the furnace is in position to close the port 12. Thus the gas nozzle at the right end of the furnace is cut out of communication with its regenerating chamber 9 and, consequently, there is no pull through the nozzle at the right end of the furnace. Instead the only pull is downwardly through the openings 24 at the right end of the furnace and into the chambers 14 and 15 in communication therewith. Consequently the outflowing products of combustion will not have the destructive effect upon the gas nozzle which would be the case should certain of these gases be pulled out of the furnace through the nozzle. When the flow of gases through the furnace is reversed, the two valves 19 are simultaneously shifted so that the gases will pass into the nozzle 2 at the right of the furnace and mix with the air discharged through the openings 14 adjacent said nozzle, while the nozzle 2 at the left of the furnace will be cut out of communication with its regenerating chamber 9 so that the outflowing products of combustion can only escape through the openings 24 at the left end of the furnace. These products of combustion escaping through the openings 24 will pass out of the furnace through both of the regenerating chambers at that end of the furnace for the reason that the port 16 is open and a quantity of the gas is thus free to flow through said port from chamber 14 to the regenerating chamber 2.

In order to further reduce the destructive action of the heat upon the discharge ends

of the nozzles 2, the water jackets 3 are employed, together with the pipes communicating therewith.

By providing valves such as described and as illustrated in Fig. 7, broad bearing faces 70 are presented so that the valves will slide readily on their supporting surfaces without turning. As shown particularly in Fig. 6 the base 18 of each valve has its side edges beveled as at 27 and angular recesses 28 are formed under the ports 12 and 16 for the reception of the base which, when projecting into these recesses, binds the valve tightly in position across the adjacent port.

It is to be understood that any suitable connections may be provided between the valves 19 and the pistons 25. Such connections may be yieldable as indicated at 23 so as to insure the valves remaining on their seats in spite of any slight movement of the piston in the cylinder. It will also be understood that the arrangement of valves shown is but one of many in which the circulation of gases may be controlled.

Importance is attached to the fact that when communication is cut off between gas nozzle and the gas chamber, communication is at the same time established between the gas checkers and the furnace so that the checkers will have as much heat as though they were pulling gas through the ports communicating therewith.

What is claimed is:—

1. In a furnace of the reversing or regenerating type, a hearth chamber, nozzles for discharging gas into said chamber from opposite ends thereof, a gas regenerating chamber at each end of the furnace, there being passages connecting each of said gas generating chambers with its nozzle, an air regenerating chamber at each end of the furnace, each of said last named chambers having passages discharging into the furnace at opposite sides of the adjacent gas nozzle, and a valve mounted in each gas regenerating chamber, the valve at the outflow end of the furnace being shiftable to open communication between the adjacent gas regenerating chamber and the air regenerating chamber and to close communication between the gas regenerating chamber and its gas nozzle, and a valve at the inflow end of the furnace being shiftable to close communication between the two adjacent regenerating chambers and to open communication between the gas regenerating chamber and its nozzle, and means for simultaneously shifting said valves to said positions.

2. A furnace of the reversing or regenerating type including a hearth chamber, opposed nozzles for directing gas into said chamber, air and gas regenerating chambers at each end of the furnace, each air regenerating chamber being in constant communication with the hearth chamber, the air regenerating chamber being shiftable to open communication with the hearth chamber and to close communication with its nozzle, and the gas regenerating chamber being shiftable to open communication with the hearth chamber and to close communication with its nozzle, and means for simultaneously shifting said valves to said positions.

imunication with the interior of the furnace through openings at opposite sides of the end of the adjacent nozzle, each of said nozzles being adapted to communicate with 5 the adjacent gas regenerating chamber, and means for simultaneously establishing communication between the air and gas regenerating chambers at the outflow end of the furnace and the interior of the furnace, clos- 10 ing communication between the nozzle at said end of the furnace and its gas regener- ating chamber, and opening communication between the gas regenerating chamber at the inflow end of the furnace and its nozzle.

In testimony that I claim the foregoing 15 as my own, I have hereto affixed my signature in the presence of two witnesses.

JAMES W. BARNES.
